METALLURGICAL FURNACE

Hugh S. Cooper, Cleveland, Ohio, assignor of one-half to Frank H. Wilson, Cleveland, Ohio

Application March 21, 1942, Serial No. 435,678

6 Claims. (Cl. 13—8)

This invention relates to metallurgical furnaces and more particularly to metallurgical furnaces for use in the practice of a distillation process for the production of vaporizable metals, such as magnesium.

One of the objects of the present invention is to provide an improved metallurgical furnace.

Another object is to provide a metallurgical furnace suitable for use in the production of a vaporizable metal, such as magnesium.

Still another object is to provide a metallurgical furnace suitable for the practice of the distillation method of producing magnesium described and claimed in my co-pending application Serial No. 434,078 filed March 10, 1942.

Other objects and advantages will be apparent as the invention is more fully hereinafter disclosed.

In accordance with these objects I have devised the metallurgical furnace illustrated in the accompanying drawings, wherein—

Fig. 1 is a sectional side elevational view of the metallurgical furnace of the present invention;

Fig. 2 is a sectional view of the same along plane 2—2 of Fig. 1 illustrating one feature of the present invention;

Fig. 3 is a sectional view along plane 3—3 of Fig. 1 illustrating a second feature of the present invention;

Fig. 4 is a sectional view along plane 4—4 of Fig. 1 illustrating a third feature of the present invention;

Fig. 5 is a view illustrating a modification of one feature of the present invention;

Fig. 6 is a view along plane 6—6 of Fig. 1;

Fig. 7 is a side elevational view of a complete furnace assembly including an auxiliary furnace (shown in section) utilizable with the furnace of the present invention when adapted to the production of magnesium; and

Fig. 8 is a sectional view of the auxiliary furnace of Fig. 7 shown in a second position.

Referring to the drawings, the furnace design illustrated is particularly adapted to the production of magnesium by the method described and claimed in co-pending application Serial No. 434,078 filed March 10, 1942, above identified.

In accordance with this said method, magnesium oxide is intimately mixed with a non-vaporizable reducing agent, such as an aluminum-silicon alloy containing from about 20 to not over about 50% silicon, each in finely divided condition and the mixture is compacted under pressure to porous agglomerates, known in the art

generally as briquettes, of any desired and convenient size, and the briquettes, are heated to elevated temperatures above the vaporization temperature or boiling point of magnesium and up to about 1600° C. in a container closed to the atmosphere and in an inert atmosphere at a pressure within the range 0.0 to 766 millimeters of mercury.

At temperatures above the vaporization temperature or boiling point of magnesium at the gas pressure employed, the aluminum-silicon alloy reduces the magnesium oxide according to the equation:

The magnesium produced in this reduction reaction volatilizes or vaporizes from the heated briquettes and may be collected in a suitable condenser chamber having a temperature below the boiling point of magnesium and preferably substantially below the melting point of the magnesium.

I have found that the rate of reduction of magnesium oxide by the aluminum-silicon alloy at any temperature above the boiling point of magnesium at the pressure employed, is markedly effected by the rapidity with which the magnesium vapor phase is removed from the reduction reaction zone and that by locating the condenser surface relatively close to the reaction zone thereby providing a relatively short path of travel for the vapor, the reaction temperature may be markedly lowered and the reaction time interval at the lower temperature is materially shortened.

This condition is provided in the furnace arrangement illustrated in the drawings. As may be seen from the drawings (Fig. 1) the furnace consists of two separable parts or sections, consisting of a base B and a vaulted cover C with means S to hermetically seal the two parts B and C together.

Base B is provided with a shallow hearth H consisting of refractory material, such as aluminum oxide, high melting fire clay, and the like, preferably surface interiorly with aluminum silicate ($\text{Al}_2\text{O}_3 \cdot 2\text{SiO}_2$).

In the bottom of hearth H is located a plurality of electrical resistors R which, for purposes of the present invention, may be comprised of any suitable high resistance electrical conductor, such as one of the heretofore well known Cr-containing alloys of Fe, Co, Ni, or of molybdenum rod, or may be comprised of carbon.

Vaulted cover section C is provided with an

interiorly located depending condenser A which may be cooled interiorly by liquid or gaseous media, and which is substantially centrally located therein in concentric spaced relation to the inner side walls of the cover C which may or may not be lined with refractory material 10, for example, aluminum-silicate ($Al_2O_3 \cdot 2SiO_2$). The condenser A provides a condensing surface 11 in relatively close spaced relation to briquettes 12 disposed on hearth H upon which the magnesium 13 is to be collected by condensation during operation of the furnace.

The particular size, shape and configuration of condenser A may be varied widely without essential departure from the present invention as may also the size, shape and configuration of surface 11. The design illustrated, however, when employed with substantially round or annularly shaped sections B and C appears to produce the best results, particularly for use in combination with the auxiliary means illustrated in Fig. 7, as will be more fully hereinafter described.

The location of condenser A centrally within the furnace cover C in the manner shown affords a means for directionally condensing the magnesium upon surface 11. For this reason, I prefer to shape condenser surface 11 as a portion of a sphere so that radiated heat energy from hearth H will be reflected outwardly therefrom and in major part onto the side walls of the cover C to help maintain the said side walls at a relatively higher temperature than condenser surface 11.

The cooling of condenser A may be effected in a plurality of different ways without essential departure from the present invention. It is desired to maintain the deposit of metal 13 collected on surface 11 at a temperature below the melting point but in a range of temperatures favorable for the formation of relatively large sized metal crystals from the condensing vapor phase, particularly where magnesium is the metal produced. Magnesium has a melting point approximating 650° C. The cooling means provided should be adapted to maintain the magnesium deposit 13 at a temperature in the range 350° C. to 450° C. The temperature of the magnesium in the vapor phase is at least 1100° C. and, depending on the temperature of the briquettes on hearth H, may be as high as 1600° C. The cooling means provided must be such as to carry away rapidly the thermal units evolved by the magnesium on condensation on surface 11 of the condenser. The latent heat of fusion of magnesium is about 72 Cal./gram and the latent heat of vaporization at 965° C. approximates 2020 Cal./gram according to the most reliable data available.

This has been found to be effectively accomplished by feeding a liquid, such as water, maintained at a temperature of 35-40° C., at a controlled pressure through pipe 14 directly onto the inner face of the spherical shaped condenser surface 11 at the point of closest approach of the surface to the heat zone on hearth H and dispersing or distributing the same along the curved inner face of surface 11 in the space gap between said inner face and spherical shaped perforated plate 15, the perforations in plate 15 being designed to effect distribution of the liquid at the pressure employed within the said space gap, such as, for example, by grading the size of the perforation openings 40 and the total number thereof from the center outwardly, the larger diameter openings being located the farthest distance

from the pipe 14 and adjacent the outer edges of plate 15.

To attain this result the discharge end of inlet pipe 14 is substantially centrally located in plate 15 and means (not shown, but common in the art) is provided to feed liquid at a substantially constant temperature of about 40° C. to pipe 14 under a regulated and controlled pressure, and means such as dual outlet or discharge pipes 16-16' is provided to carry off the liquid from the interior of the condenser.

Condenser A is preferably comprised of metal, such as low carbon, iron or steel, to facilitate the rapid transfer of heat energy from the surface 11 to the water flowing interiorly the condenser. The manner of sustaining condenser A interiorly the cover C may be varied widely without essential departure from the present invention. The arrangement shown seems to be the most convenient and practical. In this arrangement, the top of condenser A is provided with an annular collar 17 having an annular shoulder 18 adapted to engage an annular recess along the inner periphery of a centered opening in cover C which is closed by cover plate 19 having a plurality of bolts 20 passing therethrough, the threaded ends thereof engaging in complementary threaded recesses in the top of collar 17 with an annular gasket 21 disposed in sealing relation therebetween.

Cover C is also provided with a two-way valved port opening 22 for connecting the interior of the furnace to an exhausting means, such as a standard type vacuum pump V (Fig. 7) and an inert gas flushing means, such as a tank T (Fig. 7) of inert gas, such as hydrogen or helium, under pressure.

In the present invention, one of the most desirable features is the means S provided to hermetically seal cover C onto base B. This is effected by means of an annular resilient sealing member, such as a rubber gasket 23 sustained in fixed position on the outside of base B in channel extension 24 formed integrally with the outer wall of base B and coacting with annular rib extension 25 on the bottom of cover C. To prevent excessive heating of gasket 23 the rib extension 25 is provided with a cooling means, such as an annular water cooling chamber 26. Alternatively, cooling chamber 26 may be disposed around gasket 23 and channel 24 without essential departure from the present invention.

The sealing means S provided, namely, coacting parts 23 and 25, are automatically operative to effect sealing of the furnace interior to the atmosphere as cover C is located in position on base B and to become a vacuum tight seal immediately following a reduction of pressure of the furnace interior by operation of the exhaust means V and to maintain the seal as long as the pressure interiorly the furnace is less than atmospheric pressure. Upon the return of the pressure interiorly the furnace to atmospheric pressure (or above), the normal weight of the cover C is sufficient to maintain a gas tight joint between these annular parts 23 and 25, but the parts are readily separable by movement of cover C vertically upward from base B.

In such a furnace it is usually difficult to maintain a vacuum tight seal around the leading-in conductors or electrodes passing through the furnace walls to resistors R in base B. I have provided a vacuum seal for this purpose which is shown in section on the left of Fig. 1 and in more detail in Fig. 4. In this arrangement, electric

current for energizing resistors R is delivered from any convenient source by conductors 30-30' to water cooled metal electrodes 31-31' which extend to the interior of base B through openings in the wall 32 thereof and are connected electrically by a sliding contact to connector 33. The opening in the furnace wall through which water cooled electrodes 31-31' extend are each provided with an annular extension 34-34' in the outer face of which is disposed an annular gasket 35 comprised of resilient material such as rubber and on each electrode 31-31' is located a collar 36-36' on which is provided an annular rib extension 37-37' in a position to engage gasket 35. A plurality of threaded bolts 38 are provided passing through unthreaded openings in collars 36-36' to engage in correspondingly threaded recesses in extension 34 to an extent at least sufficient to draw collars 36-36' and electrodes 31-31' in the direction towards the furnace interior a sufficient distance to bring rib extension 37 into sealing engagement with gasket 35.

With this arrangement electrodes 31-31' each are free to move inwardly a further distance as the pressure of the furnace interior is lowered, but are restrained by bolts 38 from moving outwardly beyond sealing position of rib 37 with gasket 35. Accordingly, as the furnace pressure is reduced the seal engagement between rib 37 and gasket 35 becomes greater. This movement of electrodes 31-31' inwardly must be compensated for by providing a sliding contact between electrodes 31-31' and connectors 33-33'.

In the practice of the method invention of said co-pending application, it is desirable to heat the briquettes in hearth H to the reduction reaction temperature by direct contact of the briquettes with the incandescent electric resistors R. This is desirable primarily because not only is the magnesium oxide content of the briquettes a high refractory material with a relatively low thermal conductivity but the reaction product aluminum-silicate is of similar refractoriness and low thermal conductivity.

Accordingly, I prefer to provide a plurality of resistor elements R located in spaced relation in the bottom of hearth H and on which the briquettes 12 may be deposited for heating by direct contact therewith to the reaction temperature. These resistor elements R may be electrically connected in parallel between electrodes 31-31' as shown in Fig. 1 or in series, as indicated in Fig. 5. The current when connected in series is less than when connected in parallel but the parallel connection may be used with low voltages.

Referring now to Figs. 7 and 8, a complete assembly for the production of magnesium in the furnace of the present invention is shown. In the manufacture of magnesium by distillation as contemplated by the practice of the method described and claimed in my said co-pending application, the condensed magnesium metal is highly pyrophoric due to the fact that the surface of the metal is not coated with a protective oxide film.

In accordance with my invention, the maintaining of a relatively high temperature within the range 350-450° C. during the condensation of the magnesium vapors onto surface 11 of condenser A provides for the formation of relatively large sized crystals or aggregates of crystals of magnesium metal. Following the complete reduction of the magnesium oxide in briquettes 12,

as may be determined by observation through window W and by experiment ascertained to occur within a determined time interval of heating for any given mass of briquettes 12 of determined MgO and Al-Si content, the furnace interior is allowed to cool to a low temperature before releasing the vacuum or low pressure formed therein.

I then gradually raise the pressure within the furnace by bleeding slowly therein an inert gas, such as hydrogen or helium, which contains a relatively low percentage of an oxidizing gas, such as water vapor (up to 5%). By thus slowly oxidizing the surface of the magnesium deposit on condenser A, the heating up of any of the crystals or particles of metal to a temperature at which rapid oxidation will occur is substantially inhibited. As the pressure approximates atmospheric pressure or above, cover C may be vertically raised from base B by motor hoist means K and transferred horizontally to a position over auxiliary melting furnace M (Fig. 7) and lowered vertically to a position immersing condenser A in a molten salt bath D contained in crucible E of the furnace M. By a proper design of furnace M and crucible E cover C may be adapted to form a cover over crucible E as shown in Fig. 8, so that the magnesium will be protected from contact with the oxidizing gases discharging through flue F in furnace M during melting from condenser A. Furnace M may be heated by gas burner means G as shown (Fig. 7) or alternatively by an electrical resistance heating means, if desired or deemed advisable, without essential departure from the present invention.

Molten salt bath D preferably consists of a mixture of potassium and sodium chlorides, melting at about 650° C., but many other fusion mixtures are available in the art for the purpose and the bath composition, per se, forms no particular part of the present invention.

It is believed apparent from the above description of the metallurgical furnace of the present invention and from the drawings illustrating the same that the invention may be widely modified without essential departure from the present invention and all such modifications and adaptations thereof are contemplated as may fall within the scope of the following claims.

What I claim is:

1. In a vacuum furnace consisting of base and cover sections each exteriorly provided with a vacuum tight shell and adapted to seat one upon the other to provide an enclosed area to be evacuated by means extending through the shell of one of the said sections, means providing a vacuum tight joint therebetween while the said sections are seated one upon the other while the interior pressure is below atmospheric pressure, but providing for ready separation of the parts at interior pressures approximating atmospheric pressures and above, said means comprising an annular gasket consisting of resilient material mounted upon the outer periphery of the shell of said base section adjacent the open end thereof and facing substantially upward and an annular rib member mounted upon the outer periphery of the shell of said cover section adjacent the open end thereof and extending beyond the said open end of said cover section a distance adapted to bring the said rib member into engagement with the said annular gasket when the cover section is seated upon the said base section with the open end of the cover section held in spaced relation to the open end of the

said base section with the cover section free to move towards the base section against the resiliency of said gasket as the pressure of the area enclosed by said base and cover sections is lowered below atmospheric pressure, and means associated with the said gasket and rib extension to maintain the same at a temperature below the temperature at which the resiliency of the said gasket is detrimentally effected.

2. A vacuum furnace for the distillation production of readily vaporizable metals, said furnace comprising in combination an open-ended base section enclosed by a hermetic shell and provided with a relatively shallow hearth in the bottom of which hearth is located an electrical resistance heating means for heating material disposed in the hearth and an open-ended vaulted section enclosed by a hermetic shell and provided with an interiorly depending water cooled condenser chamber and with means connecting the cover interior to an evacuating means, and means disposed about the periphery of each said section adjacent the open ends thereof to hermetically seal the two said sections together when the said cover section is seated in covering position over the open end of said base section at all pressures below atmospheric pressure, said means comprising an annular gasket consisting of resilient material sustained facing substantially upward about the outer periphery of said base section adjacent the open end thereof and an annular rib extension depending from the outer periphery of said cover section and extending beyond the open end of said cover section a distance adapted to bring the forward edge of the said rib extension into hermetic seal engagement with the upwardly facing surface of said gasket when the said cover section is seated upon the said base member with the open end of the said cover section spaced away from the open end of the said base section a distance providing for the free movement of the cover section towards the said base section against the resiliency of said gasket as the pressure of the area enclosed by the two said sections is lowered below atmospheric pressure to as low as a high vacuum.

3. The furnace of claim 2, wherein the said dependent water cooled condenser in said cover section is adapted to provide a relatively short path of travel for the metal vapors driven off from said hearth by locating the major condensing surface of said condenser in close spaced relation to the open end of said base section with the said cover in seated position thereon.

4. A metallurgical furnace for the distillation production of vaporizable metals, said furnace consisting of a base section and a cover section, the base section being provided with a relatively shallow horizontally located hearth having an electrical resistance heating means disposed in the bottom thereof in substantially direct contact with material disposed in the said hearth and the said cover section being vaulted and provided with a depending water cooled condenser

chamber disposed in covering position over said hearth in the base member and in relatively close spaced relation thereto providing a short distance of travel for metal vapors arising from the said hearth, each said section being provided with an outer shell consisting of material impermeable to gases at all pressures, and means to hermetically seal the said cover section in covering position on said base section, said means consisting of an annular gasket comprised of resilient material located in the periphery of said base section adjacent the open end thereof and an annular rib extension of the peripheral surface of said cover section adjacent the open end thereof and extending beyond the said open end a distance adapted to provide for the gravity weighted engagement of the forward edge of the said rib with the face of said gasket when the cover section is seated on said base section with the cover section free to move against the resiliency of the said gasket as the pressure of the area enclosed by the two sections is lowered below atmospheric pressure and to return to first position as the pressure of the said area returns to atmospheric pressure, and means passing through one said section to evacuate the said enclosed area.

5. A vacuum metallurgical furnace for the distillation production of magnesium, said furnace consisting of a substantially cylindrical base section provided with an annular horizontally located channel member facing upwardly about its outer periphery adjacent the top thereof with an annular gasket of resilient material located therein and with a substantially dish-shaped hearth having an electrical resistance heating means located in the bottom thereof, and a vaulted cover section provided with a refractory lining and with an annular depending rib extension about its outer periphery adjacent the open end thereof having a diameter and location adapting the same for seating engagement on the said annular gasket when the said cover is disposed in covering position on said base section, an interiorly depending hollow condenser chamber in the top of said cover, said chamber including cooling means to maintain the exterior surface of at least the bottom surface thereof at a desired temperature, means to exhaust gases from the furnace interior and means to introduce a desired gas atmosphere at a desired low pressure less than atmospheric pressure within the said furnace interior.

6. In combination, the furnace of claim 5, and a melting furnace provided with a crucible having an outside diameter less than the inner diameter of the said vaulted cover and an inside diameter greater than the outside diameter of said condenser chamber and transfer means for transferring the cover from covering position on said base section to covering position on said crucible with the condenser chamber thereof immersed in a molten salt bath contained in said crucible.
